FRANK J. MERKLE, OF ZANESVILLE, OHIO.

DESIGN FOR A CLAY BUILDING-BLOCK.

No. 37,811.

Specification for Design.

Patented Feb. 6, 1906.

Application filed August 14, 1905. Serial No. 274,232. Term of patent 14 years.

To all whom it may concern:

Be it known that I, FRANK J. MERKLE, a citizen of the United States, residing at Zanesville, in the county of Muskingum and State of Ohio, have invented a new, original, and ornamental Design for a Clay Building-Block, of which the following is a specification, reference being had to the accompanying drawing, forming a part thereof.

The figure is a view in perspective of a building-block, showing the design.

I claim—

The ornamental design for a clay building-block as shown.

In witness whereof I have signed my name to this specification in the presence of two subscribing witnesses.

FRANK J. MERKLE.
